CLAIM

The ornamental design for a speaker, as shown and described.

DESCRIPTION

FIG. 1 is a perspective view of a first embodiment of a speaker showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and

FIG. 7 is a right side elevational view thereof.

FIG. 8 is a perspective view of a second embodiment of a speaker showing our new design;

FIG. 9 is a top plan view thereof;

FIG. 10 is a bottom plan view thereof;

FIG. 11 is a front elevational view thereof;

FIG. 12 is a rear elevational view thereof;

FIG. 13 is a left side elevational view thereof; and,

FIG. 14 is a right side elevational view thereof.

The broken lines immediately adjacent the shaded areas represent the bounds of the claimed design while all other

(Continued)

broken lines are included for the purpose of illustrating portions of the speaker; the broken lines form no part of the claimed design.
